LEVER OPERATED SNAP SWITCH

Robert H. Bentley, Hartford, Conn., assignor to
The Arrow-Hart & Hegeman Electric Company, Hartford, Conn., a corporation of Connecticut

Application December 20, 1930
Serial No. 503,837

2 Claims. (Cl. 200—6)

This invention relates to lever operated snap switches of the type shown in the Guett Patent No. 1,511,809, patented October 14th, 1924. However the switch shown in that patent is capable 5 of breaking the circuit on only one side of the line.

It is an object of my invention to provide a lever operated switch which will break the circuit on both sides of the line so as to leave the 10 electrical device controlled by the switch, "dead". Another object is to make said switch of a few, inexpensively manufactured parts, the majority of which may be stamped from sheet stock and riveted together.

15 In the drawing:—

Fig. 1 is a side elevation view of my invention with a portion of the casing broken away to show the switch operating mechanism.

Fig. 2 is a section view of the switch, the section being taken on the line 2—2 of Fig. 1.

Fig. 3 is a section view taken on line 3—3 of the Fig. 2.

Fig. 4 is a detailed section view of the anti-friction roller employed in my switch.

20 Referring to the drawing, the switch base 10 is made up of a plurality of laminations L of insulating material which may be held together by bolts or rivets passing through the laminations and through a sheet metal yoke 12, all as shown and described in the Guett Patent No. 1,744,629, patented January 21, 1930. Also as 25 shown in that patent, a cavity 18 with an arcuate bottom, may be formed in the base, by cutting away the central portions of several of the interior 30 laminations. The switch is operated by a pivoted thumb lever 14 which stresses a coil spring 16 to cause an anti-friction roller 17 to roll along the arcuate bottom of the recess. Switch operating mechanisms of this type are well known and 35 the kind used in my switch is shown and described in the Guett Patent No. 1,511,809. Therefore a more detailed description of the switch mechanism need not be given, especially since it is obvious that this invention is not limited 40 to any one switch operating mechanism.

In my switch, the anti-friction roller 17 is made 45 up of a dumbbell shaped member 20 of insulating material which has mutually insulated metallic caps 22 encasing the enlarged ends thereof, the 50 inner edges of these caps being turned over toward the central portion of the member as at 24, so that the caps will hold themselves upon the insulating portion of the roller.

As the roller is moved along the arcuate bed 55 of the cavity 18 it makes and breaks contact

between two pairs of stationary contacts 30, 31 and 32, 33, which have portions disposed within the cavity at one end of the arcuate bed. The contacts 32, 33 are adapted to be bridged by one cap of the anti-friction roller while the contacts 30, 31 are adapted to be bridged by the other cap of the roller. The contacts 31 and 33 are alike and may be substantially Z-shaped, or of any other suitable shape. I prefer to make them with terminal portions 36 extending out 60 of the casing to facilitate connecting the switch in a circuit. As shown, these contacts are made from sheet metal, the upper or terminal portion 36 thereof being offset laterally within the base toward the central lamination C. The offset portion 65 is narrowed and affords an anchoring means to help hold the contact in fixed position. The lower portion of the contacts has an arcuate contacting surface lying flush with or rising slightly above the bed of the cavity 18 so that 70 the roller will roll upon this arcuate contact surface when it is in the end of the cavity with the stationary contacts. Lying adjacent the stationary contacts 31, 33 are the contact buttons 30, 32 so that as the peripheries of the roller caps 75 22 engage with the contacts 31 and 33, the head portions of these caps will engage the contact buttons 30, 32. The contact buttons 30, 32, are mounted upon flat resilient metallic spring members 38 which are riveted to wire terminals 40 80 85 which project from the opposite end of the casing from the wire terminals 36. Certain of the laminations of the base are recessed to accommodate the wire terminals 40; and the laminations next adjacent to the wire terminals 40 are recessed to 90 accommodate the spring members 38. The laminations which form the side walls of the cavity 18, and which in the present case are the same laminations which are recessed to accommodate the wire terminals 40, are also recessed adjacent 95 the contacts 31, 33 to receive the contact buttons 30, 32. In order to insulate the projecting portions of the wire terminals 36, 40 from one another, I prefer to extend the central lamination 100 C of the base beyond the base in an amount equal to or greater than the extension of the wire terminals beyond the base.

From the foregoing it will be seen that as the anti-friction roller is compelled to move along the arcuate bed of the base, it will, when at one end of the cavity 18, not engage any contacts, but when it is moved to the other end of the cavity the caps 22 will engage the stationary contacts 30, 31 and 32, 33 respectively and permit 110

passage of current from the terminals 40 through caps 22 to the terminals 36 or vice versa.

Thus it will be seen that the two sides of the circuit may be connected to the terminals 40 and 36 and the double break in the circuit incident to operating the switch will completely isolate from the source of power any electrical device which is controlled by the switch.

I claim:—

- 10 1. In an electric snap switch, a laminated insulating base having a cavity therein, recesses within certain of said laminations, two pairs of switch contacts within said recesses, snap switch mechanism in said cavity, an anti-friction roller adapted to be moved in said cavity by said switch mechanism, said roller having metallic portions thereon insulated from each other, said metallic portions being adapted to engage one contact of each pair with one surface, and the other contact of each pair with another surface, one contact of each pair having a resilient portion extending within said base behind a side wall of said cavity from one end of the base toward the other to a point adjacent the other contact of that pair, said one contact extending through an opening in

25

the side wall of said cavity in position to be engaged by said roller while said roller engages said other contact.

2. In an electric snap switch, a laminated insulating base, having a cavity therein, recesses within certain of said laminations, two pairs of switch contacts within said recesses, snap switch mechanism in said cavity, an anti-friction roller adapted to be moved in said cavity by said switch mechanism, said roller having metallic portions thereon insulated from each other, said metallic portions being adapted to engage one contact of each pair with one surface, and the other contact of each pair with another surface, one contact of each pair having a resilient portion extending within said base behind a side wall of said cavity from one end of the base toward the other to a point adjacent the other contact of that pair, said one contact extending through an opening in the side wall of said cavity in position to be engaged by said roller while said roller engages said other contact.
